COMB WITH RECEPTACLE FOR LIQUIDS

Ettore Dominici, Turin, Italy

Application July 1, 1936, Serial No. 88,282
In France June 18, 1936

4 Claims. (Cl. 132—13)

This invention relates to a comb having a receptacle adapted to contain liquids, such as hair dye, and provided with means for uniformly delivering said liquid to the individual comb teeth and from these to the user's hair.

An object of this invention is to provide a comb comprising a hollow back section open on one side constituting the receptacle and a comb proper, which may be fitted on the open side of the body 10 to close this tightly, and is provided with means for uniformly distributing the liquid along the inner sides of the individual teeth.

A further object of this invention is to provide a comb of the character specified, in which the 15 teeth section is obtained by cutting sheet metal to form a number of parallel slits, said sheet metal being folded along the middle line perpendicular to the slits to form a row of hollow teeth.

A still further object of this invention is to provide 20 a comb of the character specified, in which between the two branches of the teeth section an insert of cut sheet metal is interposed which has teeth portions extending within the corresponding comb teeth and a back portion, on the faces 25 whereof there are formed grooves of variable section and increasing in length from the ends towards the center of the comb, in order to suitably distribute the liquid and prevent liquid leakage at the ends.

30 A further object of the invention is to provide a comb in which the teeth increase in length from the ends towards the middle portion, to obtain a uniform distribution of the liquid to the user's hair.

35 Further objects and features of the invention will be evident from the accompanying drawing, wherein:

Figure 1 is a side elevation of the comb, partly 40 in section;

Figure 2 is a cross section;

Figure 3 shows the teeth section blank;

Figures 4 and 5 are an elevation and a plan view, respectively, of the insert;

45 Figures 6 and 7 show on an enlarged scale a partial cross section and a partial plan view of the insert.

Referring to the drawing, 1 is a flat elongated 50 box open on one side and shaped to the form of the back section of an ordinary comb.

The edge 2 on the open side of said box is machined and surrounded by a bead 3 secured by welding to the edge of said open side to form a seating adapted to receive the teeth section.

55 The teeth section is obtained from a piece of

sheet metal 4 (Fig. 3) in which a number of parallel slits 5 and a marginal web 6 are formed by cutting and pressing; by bending this blank about the middle axis X—X perpendicular to the slits, a hollow tooth 7 is obtained from each strip between the slits, of which the adjacent lateral edges form elongated apertures through which the liquid is delivered to the user's hair.

A closing and distance tongue 9 is inserted into the end teeth 8. The two branches of the teeth 10 section are clamped against a delivery insert, more fully described hereinafter by screws 10 screwed into end lugs 11 on the teeth sections and insert.

As will be clearly seen from Fig. 1, the teeth 15 length gradually increases from the comb ends towards the center; this arrangement is of special importance since in normal use a greater quantity of hair is accumulated at the central 20 portion of the comb necessitating a more extensive liquid delivery surface.

To obtain a suitable delivery of liquid and prevent dripping at the ends in the vertical or nearly vertical position of the comb which is the normal 25 position taken by the comb in use, a delivery insert (Figs. 4 and 5) is provided, which is inserted between the teeth section branches. This insert comprises a back portion 12 having the same profile as the back portion of the teeth section and a number of teeth 13 extending in the intermediate section teeth 7. This insert is 30 clamped between the teeth section branches by means of the screws 10 passing through the holes 14.

On both faces of the back portion 12 delivery 35 grooves 15 are formed which are of gradually decreasing length from the center towards the ends (Fig. 4) and of gradually increasing cross section from the rear edge towards the teeth 40 (Fig. 6). By this arrangement, the liquid contained in the receptacle 1 finds its way towards the delivery ports in the teeth 7 more easily towards the middle portion than at the ends of the comb. Consequently, when during use the comb 45 is held vertical or almost vertical, the greater resistance encountered by the liquid to reach the end teeth makes up for the greater hydrostatic pressure in the teeth lower in level, whereby supply of liquid to the central portion, where there is 50 normally a greater mass of hair, is maintained substantially constant whatever the position of the comb may be.

This suitable distribution of liquid is improved 55 by the concave form of the rear edge of the teeth

section and insert which causes the liquid to accumulate towards the central portion of the comb.

The grooves 15 on one side of the back portion 12 are staggered with respect to those on the other side for constructional reasons.

The insert is provided with a central stud 16 which is fitted, in assembling the comb, into a sleeve 17 solidly connected with the bottom of 10 the receptacle 1 and carries screwed thereon on its portion projecting to the outside a nut 18 which tightly secures the teeth section against the receptacle.

The sleeve 17 prevents spilling of the liquid 15 during filling of the receptacle 1, which is of course effected at the open forward side after removal of the teeth section.

To facilitate manipulation of the comb, the latter is provided with a handle 19 fixed between 20 the branches of a strap 20 welded or otherwise fixed to an end of the receptacle 1; the handle is thus above the bead 3 of the receptacle, which prevents soiling of the hands in case of liquid leakage between the web 2 and edge 6 owing to 25 improper mounting of the teeth section in the receptacle or other causes.

It will be understood that the form and constructional details may be varied according to practical requirements, without departing from 30 the scope of this invention.

What I claim is:

1. In a reservoir comb the combination with a box-like receptacle having one open side and adapted to contain a liquid, of a teeth section 35 adapted to be clamped in a liquid-tight manner between the walls defining the open side of said receptacle and obtained from sheet metal cut to form a plurality of parallel slots and bent along the middle line perpendicular to the slots 40 to form a row of hollow teeth having narrow lateral slits to deliver the liquid over all the length of each tooth and means in said teeth section and in said receptacle to deliver the liquid substantially in a uniform manner to the individual 45 teeth.

2. In a reservoir comb the combination with a box-like receptacle having one open side and adapted to contain a liquid, of a flat seating at

the edge of each wall defining said open side of said receptacle, a bead around said seating, a teeth section tightly clamped between said seatings and obtained from sheet metal cut to form a plurality of parallel slots and bent along the middle line perpendicular to the slots to form a row of hollow teeth having narrow lateral slits for delivering the liquid along the whole length of each tooth, marginal webs perpendicular to said slots cooperating with said seating on the receptacle to afford a tight closure, an insert in said teeth section having at its rear portion grooves for delivering the liquid in a substantially uniform manner to the individual teeth. 5 10

3. Comb, as claimed in claim 2, having a closing tongue clamped in a liquid-tight manner between the two branches of each of the end teeth of the teeth section. 15

4. In a reservoir comb the combination with a box-like receptacle having one open side and 20 adapted to contain a liquid, a flat seating at the edge of each wall defining said open side of the receptacle, a bead around said seating, a teeth section clamped in a liquid-tight manner between said seatings and obtained from sheet 25 metal cut to form a plurality of parallel slots and bent along the middle line perpendicular to the slots to form a row of hollow teeth having narrow lateral slits for the delivery of the liquid over all the length of the tooth, marginal webs 30 perpendicular to said slots and cooperating with said seating on the receptacle to afford a tight closure, lugs at the back portion of the teeth section to give to said back portion a concave profile serving to guide the liquid towards the central part of the receptacle, closing tongues 35 between the branches of the end teeth of the teeth section, a comb-shaped insert fixed in said teeth section between said tongues and having the same profile as said teeth section, said insert 40 being provided on both sides of the back portion with grooves decreasing in length towards the middle portion of the comb and increasing in cross section from the rear portion towards the teeth for uniformly delivering the liquid to the 45 individual teeth. 45

ETTORE DOMINICI.
